UNITED STATES. PATENT OFFICE.

JAMES BOORMAN STRONG, OF HILLBURN, NEW YORK.

GUARD-RAIL CLAMP.

No. 921,024.

Specification of Letters Patent.

Patented May 11, 1908.

Application filed December 2, 1908. Serial No. 465,718.

To all whom it may concern:

Be it known that I, JAMES BOORMAN STRONG, a citizen of the United States, residing at Hillburn, in the county of Rockland, 5 in the State of New York, have invented certain new and useful Improvements in Guard-Rail Clamps, of which the following is a specification.

The object of my invention is to produce a 10 guard rail clamp of extreme lightness yet possessing great strength and resistance to strain and which can be easily placed in a track with minimum interference with the ties or ballast. Heretofore guard rail clamps have 15 usually been made of cast metal, but owing to the size and weight of the rails now employed and the terrific shock received from modern locomotives and rolling stock it is necessary to make such cast clamps of un- 20 wieldy size and thickness.

Among the further objects of my invention is to produce a clamp plate of rolled metal possessing the necessary strength and shock 25 resisting qualities, but which will require a relatively smaller amount of metal in its construction than a cast clamp plate and which will be easier to handle and to place in position.

In the accompanying drawings Figure 1 is 30 a side elevation of my improved guard rail clamp, the guard and track rails being shown in section. Fig. 2 represents a plan view of the same. Fig. 3 represents an end view showing the yoke for holding the parts in 35 their proper relative positions.

The clamp plate is formed from a rolled T-rail of a standard size determined by the location of its use which comprises a flange 1 and a web 2 and is bent upward at the ends 40 3 to receive the other parts of the structure. The main rail 4 and the guard rail 5 are seated upon the horizontal portion of the clamp plate and have a suitable filler block 6 between them. Spacing blocks 7 are placed 45 between the ends of the clamp and the main rail and the guard rail respectively, and one of said blocks is provided with a beveled face 8 adapted to be engaged by an oppositely beveled wedge block 9 seated between it and 50 the end of the clamp plate. Said wedge block 9 is provided with perforations 10 to receive the ends of a yoke 11 which passes under the web of the clamp plate and seats in a groove or recess 12 provided therein. Any

suitable means as nuts 13 may be provided 55 for the purpose of forcing the wedge block 9 downward against the beveled face of the block 7 and thereby hold the parts in their proper positions.

In the process of bending over the ends of 60 the clamp plate the web thereof is drawn out at the bending points indicated at 14, which necessarily weakens the clamp plate at these points and subjects the same to rupture unless an extremely heavy plate be used. In 65 order to overcome this the ends of the web are forced downward and form oppositely inclined bevels 15 and the metal is compressed or crowded down toward the weakened bending points 14 so as to fill out the 70 metal in the bends and render the web of substantially uniform thickness throughout its entire length. Preferably also the yoke which engages under the web is made substantially V-shaped and further tends to 75 strengthen the clamp at this point. By this construction an extremely strong and effective guard rail clamp is secured comprising a clamp plate formed of rolled instead of cast metal and which can be readily and easily 80 handled and placed in position in the track without sacrificing anything with respect either to durability or strength. The clamp can be easily and readily assembled and can be as easily taken apart and replaced or 85 repaired. It is also extremely simple in construction, comprises a minimum of parts and can be manufactured at relatively small initial cost.

I claim as my invention.

1. A guard rail clamp comprising a rolled T-section with a flange portion and a web portion bent upward at its ends to receive the main rail and the guard rail, the web portion being shorter than the flange portion 95 and of substantially uniform thickness throughout.

2. A guard rail clamp comprising a rolled T-section with a flange portion and a web portion and having its ends bent upward, the 100 metal of the web portion being compressed from the ends toward the bent over portion thereof to strengthen the same, substantially as described.

3. A guard rail clamp comprising a clamp 105 plate formed from a T-rail having its ends bent upward to receive the main rail and the guard rail, a filler block between the main

22

5 rail and the guard rail, and means comprising a yoke for holding said rails and block in their adjusted positions, the web of said clamp plate being of substantially uniform thickness throughout and provided with a groove to receive the said yoke, substantially as described.

This specification signed and witnessed this 24th day of November, A. D., 1908.

JAMES BOORMAN STRONG.
